[57] ABSTRACT

A tubular roller has a circumferential tubular wall provided at its opposite ends with circumferentially offset first cutouts and projections located between adjacent ones of the cutouts. The roller further has two end walls located at the opposite ends and rigidly connected with the tubular wall. The end walls each have circumferentially offset second projections received in the first recesses of the tubular wall, and second recesses which accommodate the first projections of the tubular wall.

7 Claims, 2 Drawing Figures

FIG. 1

FIG. 2

TUBULAR ROLLER

The present invention relates to a roller, and more particularly to a tubular roller. Still more particularly the invention relates to a tubular roller which can be used in roller conveyors, as reversing and supporting rollers for conveyor belts, and for other applications.

Rollers used in such applications usually have a tubular circumferential wall and two end walls which are inserted into the open ends of the tubular wall and are mounted therein. The shaft or axis about which the roller rotates is secured in these end walls either fixedly or by means of bearings. A variety of different constructions has been proposed in the art for such rollers, including the bonding, welding, press fitting and the like of the end walls to the tubular wall.

Another proposal in the prior art for connecting the end walls with the tubular wall of such rollers has been to form the axially spaced edges at the ends of the tubular wall so as to make them inter-engage with the edges bounding the end walls. The purpose is to obtain a sturdy and rigid seating of the end walls in the tubular wall, so as to secure them against axial displacement relative to the tubular walls as well as against relative angular movement.

A difficulty which has long been experienced in this field has been that a lasting sturdy and rigid connection between the end walls and the tubular circumferential wall is very difficult to obtain. Of course, it is possible to form an abutment shoulder either on the inside of the tubular wall adjacent the respective open end thereof, against which the end wall can abut, or else to form such an abutment shoulder on the respective end wall and have the axial end of the tubular wall abut against it. This does prevent relative axial displacement of the end wall and tubular wall, although at the cost of the relatively expensive production of such shoulder. Over a prolonged period of time during which such rollers are in operation, and if the rollers are subjected to heavy loads, it has been found, however, that a really reliable and permanent connection of the tubular wall and the end walls against relative rotational or angular displacement is almost impossible to obtain. A prerequisite for this would be to precisely fit the end walls into the tubular wall, and this in turn would require such exacting tolerances in the manufacture of these walls as to make the rollers prohibitively expensive. If the circumferential wall and the end walls are of different materials, which is quite often the case in such rollers, for instance if the circumferential wall is metal and the end walls are of synthetic plastic, then the connection between the circumferential wall and the end walls will quite quickly become loosened due to differential coefficients of thermal expansion and contraction of the two materials.

In addition, due to the inevitable relative flexing movement occurring between end walls and tubular wall when substantial stresses are applied to the roller, the connection established between the walls is loosened so that a relative rotational displacement between them can occur to a slight degree; once this has taken place, such displacement will become more and more pronounced as the connection becomes looser and looser. This is particularly true when the rollers are in more or less continuous use.

In addition, it is particularly important that in the case of large rollers of this type, or of rollers which are subjected to significant stresses, or which are not only

subjected to those stresses but are also large in dimension, the circumferential tubular wall has relatively significant wall thickness. In a roller of the type just mentioned, such wall thickness is a prerequisite for the roller to be able to withstand the forces acting upon it. However, such significant wall thickness then makes the deformation of the material at the axial ends of the tubular wall into connecting engagement with the end walls rather difficult and expensive. Evidently, therefore, further improvements in this field are desirable.

It is a general object of the present invention to provide such improvements.

More particularly, it is an object of the invention to provide an improved tubular roller of the type here under discussion, which is not possessed of the aforementioned disadvantages of the prior art.

Another object of the invention is to provide such a tubular roller in which the end walls can be readily and relatively simply secured to the opposite axial ends of the tubular circumferential wall, both against axial and rotational displacement relative to the latter, and in which such securing can be effected in such a manner as to be reliable and permanent even under the influence of high stresses and temperature fluctuations acting upon the roller.

Another object of the invention is to provide such an improved roller in which the dimensional tolerances to which the various walls must be produced in order to be able to effect the connection according to the present invention, can be such that the components can be produced economically, that is without excessively high expenses.

In pursuance of the above objects, and others which will become apparent, one feature of the invention resides in a tubular roller, which is particularly though not exclusively suitable for conveyors and the like, and which comprises, briefly stated, a circumferential tubular wall having at its opposite ends circumferentially offset first cutouts, and projections located between adjacent ones of the cutouts. End walls are provided, being located at the opposite ends of the tubular wall and being rigidly connected with the latter. The end walls each have circumferentially offset second projections received in the respective first recesses of the tubular wall, and second recesses which accommodate the respective first projections of the tubular wall.

In other words, the projections and recesses of the tubular wall mesh and inter-engage with the projections and recesses of the respective end walls. This interengagement prevents relative axial displacement of the walls and relative rotational displacement thereof, even when a roller so constructed is in continuous operation and is subjected to high loads and significant temperature fluctuations.

The rolling deformation of the circumferential wall at the opposite axial ends to establish the final connection with the end walls need thus, of course, take place only over circumferentially spaced portions of the tubular wall, thus being considerably simpler to carry out than what is known from the prior art and requiring less force than was previously necessary. For this reason, it can be employed even if the circumferential tubular wall is of relatively substantial wall thickness.

It is advantageous if the circumferential dimension of all recesses and projections is identical, and it is further advantageous if the lateral flanks bounding the projections at the opposite axial ends of the tubular circum-

ferential wall, as well as those bounding the projections on the end walls, are located in radial planes of the roller, that is in planes passing through the central longitudinal axis of the roller.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawing.

FIG. 1 is a fragmentary axial section through one end portion of the roller according to the present invention; and

FIG. 2 is a perspective exploded view of the components shown in FIG. 1, prior to their assembly.

Discussing the drawing now in detail it will be seen that the roller illustrated in FIGS. 1 and 2 has a tubular circumferential wall 10 which may be of metallic material or of synthetic plastic material. Only one end portion 12 of the wall 10 has been illustrated, together with its associated end wall 14. It is to be understood, however, that the opposite end portion of the wall 10, together with its associated end wall, will be configurated in the same manner as the end portion and the end wall which have been shown in the drawing.

Further, it is emphasized that although the roller illustrated is shown as being turnably mounted on a shaft 13, the invention is quite clearly equally applicable if the roller is mounted on the shaft 13 so that it can rotate with the same but not relative to the same. In other words, the manner in which the roller is associated with the shaft 13 is of no importance for the purposes of the invention.

The end portion 12 of the tubular wall 10 is provided with circumferentially alternating recesses 40 and projections 41. In other words, the projections 41 are the result of the formation of the recesses or cutouts 40. According to the illustrated embodiment which is not, however, to be considered limiting, the circumferential length of the recesses 40 as well as of the projections 41 is identical.

The end wall 14 has an inner annular portion or hub 15 which may be of synthetic plastic material and which is mounted on the shaft 13. The inner race 17 of a ball bearing is accommodated in the annular hub 15 between a wall 20 and a projecting nose 21. The outer race 18 of the ball bearing surrounds the inner race and the anti-friction bearing balls are designated with reference numeral 19. Race 18 abuts against the inner side of an outer annulus 26 the outer side of which is provided with a plurality of circumferentially spaced teeth 30 extending in parallelism with the axis of the annulus 26.

A ring 27 is provided having on its inner side teeth corresponding to and engaging the teeth 30 of the annulus 26; the outer side of the ring 27 (which latter is press fitted into the end portion 12 of the tubular wall 10) abuts the inner circumferential surface of the end portion 12. A projecting nose 29 of the annulus 26 retains a ring 28 which is intended to prevent the intrusion of dust or other contaminants, and which is maintained by the nose 29 in abutment with the inner side of the races 17 and 18. A further ring 32 of angled profile (see FIG. 1) has a nose 31 which extends into a correspondingly configurated groove of the annulus 26,

being received therein with a snap action. The radially extending portion of the ring 32 is abutted on its inner side by another angular-profile sealing ring 33 which is biased against it by a spring 34 as shown. The space between the rings 32 and 33 may advantageously be filled with a lubricant, such as grease, so that the necessary lubrication is assured whereas on the other side the entry of contaminants such as dust is prevented by the provision of the rings 32 and 33 which therefore protect the components 17, 18 and 19 of the bearing.

In accordance with the invention, the circumference of the end wall 14 is provided with circumferentially alternating recesses 42 and projections 43 which are dimensioned so that the recesses 42 can accommodate the projections 41 of the end portion 12, and the projections 43 can enter into and be accommodated in the recesses 40 of the end portion 12.

When the roller according to the present invention is to be assembled, the end walls 14 (one shown) are first assembled, that is the components making up the respective end wall 14 are assembled. Of course, if the end walls 14 are not of the type having a bearing incorporated as in the illustrated embodiment, they could conceivably each be of a single piece. To assemble the illustrated embodiment, however, the bearing components 17, 18 and 19 are first pushed on to the annulus 15 so that the nose 21 retains the bearing. Thereafter, the rings 33 and 32 are put in place and the annulus 26 is placed about the thus assembled components, until the nose 31 projects into the associated abutment of the recess with a snap action and the nose 20 extends behind the ring 28. Now the ring 27 is press fitted into the end portion 12 of the wall 10 and the entire end wall 14 is inserted until the slightly over-dimensioned ring 27 is pressed outwardly by it into tight press-fitting engagement with the inner circumferential surface portion 12 the end portion 12 and the nose 35 of the ring 27 snaps into the associated groove (see FIG. 1) of the annulus 26. The end wall 14 is now firmly fitted into the end portion 12 of the wall 10.

The next step in assembly is to rollingly deform the projections 41 into the recesses 42, which can be readily accomplished even if the wall thickness of the wall 10 is relatively substantial. It is clear that when this is completed, relative axial movement of the end wall 14 inwardly or outwardly of the circumferential wall 10, or relative circumferential rotational displacement of the walls 10 and 14 is completely impossible. Moreover, it is evident that this impossibility will continue even if the roller is used in continuous operation, subjected to high stresses and substantial temperature fluctuations, because of the tooth-like inter-engagement of the recesses 40 with the projections 43 and of the recesses 42 with the projections 41.

It will be appreciated that instead of the three recesses 40 and projections 41, with a corresponding number of recesses and projections provided on the end wall 14, a different number of recesses and projections can be provided on the walls 10 and 14. Similarly, the circumferential dimension or length of recesses and projections need not be identical, as is illustrated. However, this latter feature does tend to simplify the assembly of the components and is therefore advantageous.

It will be understood that each of the elements described above, or two or more together, may also find

a useful application in other types of constructions differing from the types described above.

While the invention has been illustrated and described as embodied in a tubular roller, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

I claim:

1. A tubular roller, particularly for conveyors and the like, comprising a tubular wall having opposite end portions and being provided at the latter with circumferentially alternating first recesses and first projections; and end walls rigidly connected with said tubular wall at said end portions, each of said end walls including a first section of substantially annular configuration accommodated interiorly of said tubular wall and inwardly of the respective first recesses, and each of said end walls also including a second section provided with circumferentially alternating second recesses and second projections, each of said first projections being received by and substantially filling one of said second

recesses, and each of said second projections being received by and substantially filling one of said first recesses.

2. A tubular roller as defined in claim 1, wherein said end portions have surfaces each of which is disposed between a first recess and a neighboring first projection, said surfaces being located in planes extending at least substantially radially of said tubular wall.

3. A tubular roller as defined in claim 1, each of said second sections having an outwardly directed face; and wherein each of said first projections comprises a portion extending inwardly in substantially radial direction of said tubular wall and having an outwardly directed surface which is substantially flush with the outwardly directed face of the respective second section at least in the region of the respective second recess.

4. A tubular roller as defined in claim 1, said tubular wall having an inner circumferential surface, and said first section having an outer circumferential surface, and wherein said inner and outer circumferential surfaces frictionally engage one another.

5. A tubular roller as defined in claim 1, wherein said end walls consist at least in part of synthetic resin.

6. A tubular roller as defined in claim 1, wherein at least said tubular wall is of metallic material.

7. A tubular roller as defined in claim 1, wherein the dimensions of said recesses and projections in circumferential direction of the respective walls are substantially identical.
